UNITED STATES PATENT OFFICE.

WILLIAM G. DUNN, OF CLARINDA, IOWA.

INTAKE-MANIFOLD HEATER.

Application filed December 10, 1923. Serial No. 679,835.

To all whom it may concern:

Be it known that I, WILLIAM G. DUNN, a citizen of the United States, residing at Clarinda, in the county of Page and State of Iowa, have invented certain new and useful Improvements in Intake-Manifold Heaters; and I do declare the following to be a full, clear, and exact description of the invention, such as will enable others skilled in the art to which it appertains to make and use the same.

My invention relates to improvements in intake manifold heaters which provide what is commonly known as a "hot spot" on the manifold, into contact with which the gases from the carbureter are directed, so as to heat such gases and increase their volatility and efficiency. Devices of this nature have heretofore been provided, but it is one object of my invention to provide a unique association of intake manifold, heater and carbureter, all secured together by a single set of bolts, the arrangement being such as to greatly elevate the carbureter over its usual position, with the advantage that the ingoing gases have only a short travel and consequently cannot condense and partly return to the carbureter.

Another object of the invention is to provide a unique insert adapted primarily to be introduced between the cylinder head of a motor and the exhaust manifold, said insert having a gas shunting passage for supplying hot exhaust gases to the heater above mentioned, and also being provided with a return passage for the shunted gases, the arrangement being such that the gases are forced through the one passage by pressure and are drawn from the other by suction.

Yet another aim is to provide an attachment for motors now in every day use which will be simple and inexpensive, and may be quickly and easily applied.

With the foregoing in view, the invention resides in the novel subject matter herein-after described and claimed, the description being supplemented by the accompanying drawings.

Figure 1 is a side elevation, partly in section showing a well known type of motor equipped with my invention.

Figure 2 is a perspective view showing the assembly of the intake manifold, carbureter, manifold heater, insert and connecting pipes between said insert and said heater.

Figure 3 is a plan view of the parts shown in Fig. 1, and the insert and exhaust manifold at the opposite side of the motor.

Figures 4 and 5 are vertical transverse sectional views through the invention, cut in planes between the front and rear pairs of cylinders of the motor, one view disclosing the travel of the shunted exhaust gases while the other indicates the return of such gases.

Figure 6 is a vertical sectional view on line 6—6 of Fig. 4, showing more particularly the construction of the insert.

Figure 7 is a vertical transverse sectional view, illustrating a slightly different form of construction, in which the insert is not employed.

In the drawings above briefly described, the numeral 1 designates an intake manifold which is substituted for the manifold previously used on a well known type of internal combustion motor, such as that indicated at 2. The lower side of the manifold 1 is formed with a gas inlet opening 3 and is flat around this opening, as indicated at 4. The manifold 1 is also formed with a flat upper side 5 and is provided with vertical bolt holes 6 opening through the lower and upper flat surfaces 4 and 5, sleeves 7 being formed vertically across the interior of the manifold, so that the bolt holes 6 may pass through these sleeves and there will be no danger of air leaks into the manifold.

The usual carbureter 8 is elevated above its normal position and has its attaching flange 9 disposed against the flat lower face 4 of the manifold 1, so that the ingoing gases need only travel a slight distance and there is consequently no danger of any of these gases condensing and returning to the carbureter. An open-bottomed head 10 rests on the flat upper face 5 of the manifold 1 and receives exhaust gases from the motor, to heat the upper side of said manifold, directly over the opening 3, so as to effectively heat the gases entering the motor. A single set of bolts 11 pass through the bolt holes 6, through feet 12 of the head 10 and through the attaching flange 9 of the carbureter 8, so that these bolts tightly tie the three parts 1, 8 and 10 together.

At the side of the motor, opposite the intake manifold 1, is the exhaust manifold 13, and in Fig. 7, I have illustrated a pipe 14 tapped into said manifold 13 and leading to the head 10, for supplying hot exhaust

gases to the latter. From the head 10, a flexible exhaust pipe 15 leads and if desired may join the main exhaust pipe of the motor at a suitable point.

5 Instead of using the construction disclosed in Fig. 7, it is preferable to employ that illustrated in the other figures. I provide a vertically elongated insert 16 which is adapted to be introduced between the cylinder head and the manifold 13, said insert having flat inner and outer sides to engage suitable gaskets (not shown) and having openings 17 aligning with the usual openings in the manifold and cylinder head, to 10 receive attaching screws 18. The lower end portion of the insert 16 is formed with a main exhaust passage 19 which extends entirely through the body and the upper end portion of said insert is hollow and its interior 15 communicates with the passage 19, said interior being divided by a vertical partition 20, into an exhaust gas shunting passage 21 and a return passage 22 for the shunted gases. The side wall of the passage 25 21, remote from the cylinder head, is formed with a depending lip 23 which joins to the partition 20 and serves to direct the outgoing exhaust gases, or rather some of these gases, upwardly into the passage 21. 30 The opposite side wall of the return passage 22 is provided with a similar lip 24 which guards the passage 22 against the entrance of exhaust gases from the passage 19 and causes these gases to create a suction 35 within said passage 22. A pipe 25 leads from the gas shunting passage 21, to the head 10, and another pipe 26 returns from said head to the gas return passage 22, and it will thus be seen that a continual circulation 40 of hot exhaust gases will take place through the passage 21, pipe 25, head 10, pipe 26, and return passage 22. Thus, a "hot spot" is maintained at the top of the manifold 1, to effectively heat the gases 45 entering the cylinder head.

It will be seen from the foregoing, that I have provided a simple and inexpensive construction for utilizing some of the exhaust gases to heat a portion of the exhaust manifold and thus increase the volatility of the gases entering the cylinders, from the carbureter. It will also be noted that the invention may be easily installed and will necessitate few changes in the construction 50 of the motor with which it is used. Attention may be directed to the fact however, that as the carbureter 8 is elevated, some changes must be made in the throttle control means, as indicated in Fig. 1. In this 55 view, a bracket 27 has been shown, secured to the motor base. Upon this bracket, a bell crank 28 is mounted and from this bell crank, a vertically elongated rod 29 leads to the throttle valve of the carbureter. An accelerator rod 30 is connected with the bell 60

crank 28 and another rod 31 is connected to said bell crank to be operated by the usual hand throttle control. At 32, a spring has been shown for returning the operating connections to normal positions, after operation 70 thereof to open the throttle valve to a greater or less extent.

Excellent results have been obtained from the details above described and they are therefore preferably followed, but within 75 the scope of the invention as claimed, numerous minor changes may be made.

I claim:

1. The combination with an internal combustion engine having an exhaust manifold 80 at one side of the cylinder head and an intake manifold at the opposite side of said head; of an open-bottomed casing secured upon the upper side of said intake manifold and closed by the latter, said casing extending above the cylinder head, a passage member communicating with the interior of the exhaust manifold and extending therefrom above the cylinder head, an exhaust gas passage extending over the cylinder head and 85 connecting said passage member with said casing, and an exhaust gas outlet from said casing.

2. An attachment for internal combustion engines comprising a hollow head adapted 90 to be secured on an intake manifold, an insert adapted for introduction into an exhaust gas passage, said insert having an exhaust gas shunting passage and a return passage for the shunted exhaust gases, and 95 separate passages connecting said passages of the insert with said hollow head.

3. An attachment for internal combustion motors comprising an insert adapted to be introduced into an exhaust gas passage of a 100 motor, said insert having an exhaust gas shunting passage and a return passage for the shunted gases, said passages being adapted 105 for connection with a heater to circulate the hot exhaust gases therethrough.

4. An attachment for internal combustion motors comprising an insert adapted to be introduced into an exhaust gas passage of a motor, said insert comprising an elongated body having a main exhaust gas passage opening therethrough at one end of the body, the other end of said body being hollow and having its interior in communication with said main exhaust gas passage, and a partition in said hollow end of the 110 body dividing it into an exhaust gas shunting passage and a return passage for the shunted gases, one side wall of the gas shunting passage and the opposite wall of said gas return passage having lips joining 115 said partition and extending into said main exhaust gas passage, said gas shunting and gas return passages being adapted for connection to a heater to circulate the hot exhaust gases therethrough.

110

115

120

125

130

5. An intake manifold having an inlet opening in its lower side and a flat face about said opening, said manifold also having a flat upper face over said opening and 10
5. vertical bolt holes opening through the flat upper and lower faces, a carbureter having an attaching flange contacting with the flat lower face, a heater contacting with the flat upper face, and bolts in said bolt holes passing also through said flange and said heater to secure the heater and carbureter to the manifold.
- In testimony whereof I have hereunto affixed my signature.

WILLIAM G. DUNN.
